corporation of Delaware

Application December 21, 1931, Serial No. 582,355
Renewed July 22, 1932

10 Claims. (Cl. 123—148)

This invention relates to ignition apparatus for a multi-cylinder internal combustion engine requiring the production of a plurality of sparking impulses during each explosion period, for example, a twelve cylinder internal combustion engine having two spark gaps per engine cylinder and having symmetrical firing intervals.

One type of ignition system to which the present invention relates is shown in my copending application Serial Number 573,602, filed November 7, 1931. This application discloses a system comprising two sparking impulse generators operated alternately and each generator providing two ignition spark impulses simultaneously. The ignition distributor of said application comprises a head having a circular row of posts connected with engine spark gaps and cooperating with two distributor rotor conductors each having a main stem which moves past the spark gap posts of the distributor and each having a plurality of branches which move past other distributor terminals arranged in another row, each terminal being connected with a terminal of a sparking impulse generating device. My said application discloses the fact that as the number of engine cylinders of the engine increases the angular spacing between certain of the sparking impulse generator terminals decreases, and the angular spacing between the spark gap posts of the distributor decreases.

It is an object of the present invention to provide an ignition system embodying some of the principles of my said application but also providing a new arrangement of spark gap posts and sparking impulse generator terminals which will permit the use of a distributor head of relatively small dimensions while maintaining sufficient distance between the various posts and terminals to prevent short circuit. Accordingly, the posts connected with engine spark gaps are arranged in two staggered rows so as to increase the distance between adjacent posts and a new arrangement of rotor branches and sparking impulse generator terminals in the distributor head is provided in order that the later terminals may be spaced apart the maximum angular distance.

Further objects and advantages of the present invention will be apparent from the following description, reference being had to the accompanying drawing wherein a preferred embodiment of one form of the present invention is clearly shown.

In the drawing:

Figs. 1 and 2 taken together constitute a wiring diagram showing a form of the present in-

vention. In Fig. 1, the circles numbered 1 to 12 respectively represent the cylinders of a twelve cylinder internal combustion engine. Each cylinder has two spark gaps A and B. Ignition current is supplied by a storage battery 20 grounded at 21 and connected by a switch 22 with sparking impulse generating devices 23 and 24 each comprising two ignition coils as shown or induction apparatus each having a secondary provided with two insulated terminals. In the disclosed form, the induction generator 23 comprises primary coils P1 and P2 cooperating respectively with secondary coils S1 and S2. The induction generator 24 comprises primary coils P3 and P4 cooperating respectively with secondaries S3 and S4. The primaries P1 and P2 are connected with a circuit interrupter 30 and the primaries P3 and P4 are connected together with a circuit interrupter 40. The interrupters 30 and 40 respectively comprise leaf spring conductors 31 and 41 which conduct current to circuit breaker levers 32 and 42 carrying contacts 33 and 43 cooperating, respectively, with grounded contacts 34 and 44. The levers 32 and 42 carry, respectively, rubbing blocks 35 and 45 which are urged by the springs 31 and 41, respectively, into engagement with a cam 49 which is driven by the engine at one-half engine speed for a four cycle engine or at engine speed for a two cycle engine. The contacts 33, 34 are paralleled by a condenser 36 and the contacts 43 and 44 by a condenser 46. As the cam 49 rotates, it operates upon the rubbing blocks 35 and 45 alternately in order to separate the pairs of contacts 33, 34 and 43, 44 respectively alternately in order to effect alternately the discharge of the generators 23 and 24.

When the contacts 33, 34 are separated, the secondaries S1 and S2 are simultaneously discharged, the spark impulses being conducted by wires 61 and 62, respectively, to posts 51 #S1 and 51 #S2 located in a distributor head 50. Separation of the pair of contacts 43 and 44 effects the discharge of the induction generator 24 and spark impulses are simultaneously generated in the secondaries S3 and S4 and are conducted by wires 63 and 64, respectively, to distributor posts 51 #S3 and 51 #S4. The four posts 51 are arranged at 90° for the twelve cylinder dual ignition and cooperate with two distributing conductors or rotors 52 and 53 mounted upon a rotor block not shown and driven by the cam shaft which drives the cam 49. The rotor 52 has a plurality of branches marked R1, R2 and R3 spaced at 60° for a twelve cylinder dual ignition

engine and likewise the rotor 53 has three branches marked R4, R5 and R6. R1 to R6 inclusive move past the posts 51 and thereby collect sparking impulses from these posts 51. The 5 rotors 52 and 53 are provided with segments 54 and 55 respectively which extend, respectively, into proximity to inner row of posts 56 and an outer row of posts 57 arranged in staggered relation. It will be understood that the posts 56 all 10 terminate in the same plane and that that plane is spaced substantially from the plane of the ends of posts 57. In this way the segment 55 can extend across the circle of the posts 56 without coming close to the lower ends of posts 56. The 15 main portions of the rotors 52 and 53 are preferably located in the same plane. Hence, the segment 54 has an upwardly extending portion 54a which moves in proximity to the posts 56.

Assuming that the cam 49 rotates clockwise, 20 it will be apparent that the contacts 33 and 34 are separated while the contacts 43 and 44 remain in engagement. When this occurs, the induction generator 23 will be discharged, sparking impulses being generated in secondaries S1 and 25 S2 and conducted to distributor posts 51 #S1, 51 #S2. These impulses will be conducted by rotor branches R1 and R4 of rotors 52 and 53 and thence by branches 54 and 55 to spark gap posts 56 #1A—S1—R1 and 57 #1B—S2—R4. The 30 indicia 1A—S1—R1 means that the spark impulse is provided for spark gap A of cylinder 1, that said impulse is generated in secondary S1 and is distributed through rotor branch R1. Similarly, the indicia 1B—S2—R4 means that a spark impulse 35 was provided for spark gap B of cylinder 1, that said impulse is generated in secondary S2 and was distributed through rotor branch R4.

When the cam 49 rotates 30° further, the contacts 43 and 44 will be separated while contacts 40 33 and 34 remain in engagement; rotor segment 54 will be moved adjacent posts 56 #2A—S3—R2; segment 55 will be moved adjacent post 57 #2B—S4—R5; rotor branch R2 will be moved adjacent terminal 51 #S3 and rotor R5 will be 45 moved adjacent terminal 51 #S4 and the other two diametrically opposite terminals 51 #S1 and #S2 will not be adjacent any of the branches of the distributor rotor conductors. Therefore, the spark impulses generated in secondary S3 will be conducted through spark gap A of cylinder 2 through rotor branch R2 and the spark impulse generator of secondary S4 will be conducted to gap B of cylinder 2 through rotor branch R5. With this explanation, the meaning of the other 50 indicia applied to posts 56 and 57 will be clearly understood.

It is therefore apparent that the arrangement 60 of posts 51 and rotor branches R1 to R6 is such as to permit the separating of posts 51 the maximum distance apart. Taking the branches R1 to R6 collectively, the angular spacing is 360° divided by one-half the number of engine cylinders or 60°. Since the rotors move 30° during intervals between firing, it is obvious that the spacing 65 of the terminals 51 must be 1½×60° or 90° to give the maximum spacing between the terminals 51. The maximum spacing could be 2½×60° or 150° but this would bring some of the terminals 51 only 30° apart which would not be desirable using a relatively small distributor head.

Obviously the present invention may be applied 70 to engines having other numbers of cylinders. For example, a sixteen cylinder dual ignition engine could be fired by two alternately operated 75 sparking impulse generators each providing two

sparking impulses simultaneously. In the case of a sixteen cylinder engine, the total number of rotor branches would be one-half the number of engine cylinders, namely 8 and the spaces of the branches would be 45°

80

$$\text{compute from } \frac{360^\circ}{N/2} = \frac{360}{8} = 45.$$

The closest space of the terminals 51 would be 1½×45°=67½°. Similarly a twenty-four cylinder engine would have a total of twelve rotor branches, six to each rotor and the spacing would be

85

$$\frac{360}{12} = 30^\circ$$

90

and the closest distance between posts 51 would be 1½×30° or 45°. This would make the other distance 135°. Possibly a better space would be 2½×30°=75° making the other distance 105°. In other words, the angular spacing between posts 51 should be 1½ or 2½ times the angular spacing of the rotor branches in order to give the best angular spacing for the terminals 51 when it is desired to make the distributor head as small as possible. The following tabulation shows how the present invention can be applied to engines having different numbers of engine cylinders.

Number of cyls.=	Spacing of segments 54 and 55=	Total No. of branches R=	Spacing of branches R=	Desirable spacing of terminals 51=	105
N.....	180°± $\frac{(180^\circ)}{N}$	N	720° N	1½ or 2½× $\frac{720^\circ}{N}$	116
12.....	180°±15°	6	60°	1½ times or 90°	
16.....	180°±11½°	8	45°	1½ times or 67½°	
20.....	180°±9°	10	36°	(1½ times or 54° (2½ times or 90°	
24.....	180°±7½°	12	30°	(1½ times or 45° (2½ times or 75°	

115

The present invention contemplates the use of a distributor having its spark gap posts arranged circularly and concentrically with other posts which are connected with sparking impulse generating means. The distributor comprises also a plurality of distributing conductor rotors equal in number to the number of spark gaps to be fired at each explosion period. Each rotor has a main segment movable past spark gap posts and a plurality of branches which cooperate in predetermined recurrent sequence with the spark generator posts of the distributor to conduct sparking impulses therefrom to certain spark gap posts of the distributor. It will be noted that each rotor branch operates with a spark generator post but once during each cycle of operation of a distributing rotor. Each cycle of operation of a distributor rotor is one sequence of operation of the rotor branches. For example, the cycle of the rotor 52 is during the operation of its branches R1, R2 and R3 once in sequence. Rotor 52 has four cycles during one revolution. In the disclosed embodiment of the invention the branches of each distributing conductor function in the order of their arrangement with respect to their arms, that is, the arms R1, R2 and R3 of the conductor 52 function in the order named. It will be noted that the branches of a conductor cooperate with the spark generator posts in the order of their arrangement with respect to the distributor, for example, the branches of the conductor 52 will cooperate with the posts S1, S3 and S2 in the order named. This invention contemplates the use of sparking generator posts which are arranged diametrically opposite in pairs, one pair 120

120

125

130

135

140

145

150

of posts being connected with one sparking impulse generating device and another pair of posts being connected with another sparking impulse generating device, said sparking impulse generating devices being operated alternately by the engine.

While the form of embodiment of the present invention as herein disclosed, constitutes a preferred form, it is to be understood that other forms might be adopted, all coming within the scope of the claims which follow.

What is claimed is as follows:

1. Ignition apparatus for internal combustion engines having N explosion periods during each engine cycle and two spark gaps fired simultaneously at each firing instant, two sparking impulse generators each providing two sparking impulses simultaneously, engine operated means for discharging the generators alternately; and distributing means comprising a head having posts each connected with a spark gap and having four sparking impulse generator terminals arranged in a circular row and arranged in pairs, the terminals of each pair being diametrically opposite, and two engine driven conducting rotors each having a segment cooperating with a part of the distributor posts and each having the same number of branches, the total number of branches of both the rotors being

$$30 \quad \frac{N}{2}$$

and the angular spacing being

$$35 \quad \frac{720^\circ}{N}$$

said branches cooperating in pairs alternately in recurrent sequence with pairs of sparking impulse generator terminals, the closest angular spacing of said terminals being

$$40 \quad \frac{720^\circ}{N}$$

times the sum of an integer and a half.

2. Ignition apparatus for internal combustion engines having a plurality of explosion periods during each engine cycle and requiring the firing of a plurality of spark gaps at each explosion period, comprising in combination, sparking impulse generating means controlled by the engine, and a distributor having circularly arranged posts connected respectively with the spark gaps and having, concentrically with said spark gap posts, other posts connected with the spark generating means, and having distributing conductor rotors having main segments which move between the spark gap posts and the spark generator posts, each rotor having a plurality of branches which operate in a predetermined recurrent sequence to receive impulses from the spark generator posts, each branch operating but once during each cycle of operation of the rotor, said cycle being the functioning of the branches through said sequence of operation.

3. Ignition apparatus for internal combustion engines having a plurality of explosion periods during each engine cycle and requiring the firing of a plurality of spark gaps at each explosion period, comprising in combination, sparking impulse generating means controlled by the engine, and a distributor having circularly arranged posts connected respectively with the spark gaps and having, concentrically with said spark gap posts, other posts connected with the spark generating means, and having distributing conductor rotors

having main segments which move between the spark gap posts and the spark generator posts, each rotor having a plurality of branches which cooperate with the spark gap posts in the order of arrangement of the branches with respect to the arm, each branch operating but once during each cycle of operation of the arm, said cycle being the functioning of the branches once through said sequence of operation.

4. Ignition apparatus for internal combustion engines having a plurality of explosion periods during each engine cycle and requiring the firing of a plurality of spark gaps at each explosion period, comprising in combination, sparking impulse generating means controlled by the engine, and a distributor having circularly arranged posts connected respectively with the spark gaps and having, concentrically with said spark gap posts, other posts connected with the spark generating means and located equi-distant in the same circular row, and having distributing conductor rotors having main segments which move between the spark gap posts and the spark generator posts, each rotor having a plurality of branches which operate in a predetermined sequence to receive impulses from the spark generator posts, the spark generator posts and the conductor rotor branches being so arranged that posts cooperate in regular succession with the branches of a conductor rotor.

5. Ignition apparatus for internal combustion engines having a plurality of explosion periods during each engine cycle and requiring the firing of a plurality of spark gaps at each explosion period, comprising, in combination, a plurality of 110

- explosion period, a branch of each rotor will be located respectively adjacent each post of a pair of diametrically opposite posts, and that the branches will cooperate with the spark gap posts in the order of arrangement of the branches with respect to the rotor, each branch operating but once during each cycle of operation of the rotor, said cycle being the functioning of the branches once through said sequence of operation.
10. 7. Ignition apparatus for internal combustion engines having a plurality of explosion periods during each engine cycle and requiring the firing of a plurality of spark gaps at each explosion period, comprising in combination, a plurality of 80

15. 8. Ignition apparatus for internal combustion engines having $\frac{N}{B}$ explosion periods during an engine cycle and requiring S spark gaps to be fired at each explosion period, comprising in combination, a plurality of spark gap posts connected respectively with the spark generating means and having main segments which move between the spark gap posts and the spark generator posts, each rotor having a plurality of branches which operate in a predetermined recurrent sequence to receive impulses from the spark generator posts, each branch operating but once during each cycle of operation of the rotor, said cycle being the functioning of the branches once through said sequence of operation.
20. 9. Ignition apparatus for internal combustion engines having a plurality of explosion periods during each engine cycle and requiring the firing of a plurality of spark gaps at each explosion period, comprising in combination, a plurality of 80

25. 10. Ignition apparatus for internal combustion engines having a plurality of explosion periods during each engine cycle and requiring the firing of a plurality of spark gaps at each explosion period, comprising in combination, a plurality of spark gap posts connected respectively with the spark generating means and having main segments which move between the spark gap posts and the spark generator posts, each rotor having a plurality of branches which operate in a predetermined recurrent sequence to receive impulses from the spark generator posts, each branch operating but once during each cycle of operation of the rotor, said cycle being the functioning of the branches once through said sequence of operation, the branches of the rotors being equiangularly spaced by an amount equal to 360 degrees divided by the total number of branches of all the rotors.
30. 11. Ignition apparatus for internal combustion engines having a plurality of explosion periods during each engine cycle and requiring the firing of a plurality of spark gaps at each explosion period, comprising in combination, a plurality of spark gap posts connected respectively with the spark generating means and having main segments which move between the spark gap posts and the spark generator posts, each rotor having a plurality of branches which operate in a predetermined recurrent sequence to receive impulses from the spark generator posts, each branch operating but once during each cycle of operation of the rotor, said cycle being the functioning of the branches once through said sequence of operation.
35. 12. Ignition apparatus for internal combustion engines having a plurality of explosion periods during each engine cycle and requiring the firing of a plurality of spark gaps at each explosion period, comprising in combination, a plurality of spark gap posts connected respectively with the spark generating means and having main segments which move between the spark gap posts and the spark generator posts, each rotor having a plurality of branches which operate in a predetermined recurrent sequence to receive impulses from the spark generator posts, each branch operating but once during each cycle of operation of the rotor, said cycle being the functioning of the branches once through said sequence of operation.
40. 13. Ignition apparatus for internal combustion engines having a plurality of explosion periods during each engine cycle and requiring the firing of a plurality of spark gaps at each explosion period, comprising in combination, a plurality of spark gap posts connected respectively with the spark generating means and having main segments which move between the spark gap posts and the spark generator posts, each rotor having a plurality of branches which operate in a predetermined recurrent sequence to receive impulses from the spark generator posts, each branch operating but once during each cycle of operation of the rotor, said cycle being the functioning of the branches once through said sequence of operation.
45. 14. Ignition apparatus for internal combustion engines having a plurality of explosion periods during each engine cycle and requiring the firing of a plurality of spark gaps at each explosion period, comprising in combination, a plurality of spark gap posts connected respectively with the spark generating means and having main segments which move between the spark gap posts and the spark generator posts, each rotor having a plurality of branches which operate in a predetermined recurrent sequence to receive impulses from the spark generator posts, each branch operating but once during each cycle of operation of the rotor, said cycle being the functioning of the branches once through said sequence of operation.
50. 15. Ignition apparatus for internal combustion engines having a plurality of explosion periods during each engine cycle and requiring the firing of a plurality of spark gaps at each explosion period, comprising in combination, a plurality of spark gap posts connected respectively with the spark generating means and having main segments which move between the spark gap posts and the spark generator posts, each rotor having a plurality of branches which operate in a predetermined recurrent sequence to receive impulses from the spark generator posts, each branch operating but once during each cycle of operation of the rotor, said cycle being the functioning of the branches once through said sequence of operation.
55. 16. Ignition apparatus for internal combustion engines having a plurality of explosion periods during each engine cycle and requiring the firing of a plurality of spark gaps at each explosion period, comprising in combination, a plurality of spark gap posts connected respectively with the spark generating means and having main segments which move between the spark gap posts and the spark generator posts, each rotor having a plurality of branches which operate in a predetermined recurrent sequence to receive impulses from the spark generator posts, each branch operating but once during each cycle of operation of the rotor, said cycle being the functioning of the branches once through said sequence of operation.
